UNITED STATES PATENT OFFICE.

JOHN J. KNAACK, OF HURDLAND, MISSOURI.

SHIM CUTTER.

Application filed April 20, 1921. Serial No. 463,039.

To all whom it may concern:

Be it known that I, JOHN J. KNAACK, a citizen of the United States, residing at Hurdland, in the county of Knox and State 5 of Missouri, have invented a new and useful Shim Cutter, of which the following is a specification.

This invention relates to a device for cutting shims such as used to fit bearings in 10 automobiles and other mechanisms, the construction of the tool being such that it is rendered especially useful in garages and automobile repair shops where it is often necessary to cut shims out of soft sheet 15 brass. At the present time it is the practice to make these shims by cutting them with ordinary shears, this being a slow and tedious task.

It is an object of the present invention 20 to provide a simple and inexpensive tool whereby, at one operation, a complete shim of the proper size and shape can be produced.

With the foregoing and other objects in 25 view which will appear as the description proceeds, the invention resides in the combination and arrangement of parts and in the details of construction hereinafter described and claimed, it being understood 30 that, within the scope of what is claimed, changes in the precise embodiment of the invention shown can be made without departing from the spirit of the invention.

In the accompanying drawings the preferred form of the invention has been 35 shown.

In said drawings—

Figure 1 is a side elevation of the tool.

Figure 2 is a face view of one of the jaw

40 blocks.

Figure 3 is a face view of the other jaw block.

Referring to the figures by characters of reference 1 designates crossed pivotally connected levers each of which is provided at 45 one end with a handle 2 while its other end is bent to form a jaw, one of the jaws being indicated at 3 while the other jaw has been indicated at 4. The two jaws are extended 50 toward each other and have flat faces

adapted to contact when the handles are drawn together. Formed in the meeting faces of the two jaws are transversely extending dove-tailed grooves 5 and 6 respectively and seated in one wall of each groove 55 is a set screw 7 the head of which is exposed upon the outer face of the jaw as shown in Figure 1.

A dove-tailed block 8 is adapted to be inserted into one of the grooves, 5, and is 60 provided on its active face with a rib or ribs 9 defining the contour of the shim to be cut. This rib is formed of hard metal preferably sharpened. A block 10, preferably formed of Babbitt metal, and which is 65 dove-tailed as shown, is insertible into the other groove 6 and is adapted to present a flat surface 11 to the rib 9. It is to be understood that both of these blocks extend throughout the width of the jaws 3 and 4 70 and are held in place by the set screws 7.

In using the device the sheet metal to be cut into shims is inserted between the jaws 3 and 4 after which said jaws are pressed together firmly by means of the handles 2. 75 This will cause the rib or ribs 9 to cut through the metal and bite into the flat surface formed by the block 10. Thus a large number of shims can be quickly cut from the soft sheet brass or other material used 80 and it becomes unnecessary to resort to the tedious and laborious process of cutting out the shims with ordinary shears.

It is to be understood that the blocks 8 and 10 can be changed at will, it being possible 85 to have a series of blocks 8 on which different arrangements of cutting ribs are provided for producing shims of different sizes and shapes.

What is claimed is:—

A shim cutter including pivotally connected levers having diverging portions, jaws integral with said portions and providing a clearance space between the jaws and the fulcrum of the lever, said jaws having flat faces movable together, there being transverse dove-tailed grooves in said faces, dove-tailed blocks detachably seated in the grooves, one of the blocks being of soft metal, both blocks having their faces flush 100

with the faces of their jaws, a cutting rib on one of the blocks cooperating with the soft metal block to cut material inserted between the jaws, and set screws extending 5 into the jaws from the outer sides thereof and engaging the blocks.

In testimony that I claim the foregoing

as my own I have hereto affixed my signature in the presence of two witnesses.

JOHN J. KNAACK.

Witnesses:

Wm. White,

Carl Wilson.
